Henry Sorenson
INVENTOR

UNITED STATES PATENT OFFICE.

HENRY SORENSEN, OF SAN FRANCISCO, CALIFORNIA.

FIREPROOF BUILDING.

Application filed December 7, 1925. Serial No. 73,717.

While my invention may be utilized in various ways, I have, in the accompanying drawings, illustrated my invention applied to the construction of fireproof floors.

5 In the said drawings:—

Fig. 1 illustrates a plan view of my invention.

Fig. 2 is a cross-section of Fig. 1 at *d-d*. On the one half of this section I have shown 10 form 1, placed on joists from flange to flange of frame 18, upon which the fireproof material 10 is poured.

Fig. 3 is a longitudinal section of Fig. 1 at *e-e*.

15 Fig. 4 is an enlarged cross-section of a pair of bands 2, with the fragment of a longitudinal section of bands 3, showing the sloping end of 3 resting on the sloping side of 2.

20 Fig. 5 is a longitudinal enlargement showing the fragment of a sloping end of reinforcement 15, resting on the sloping side of band 3, with a crosscut section of another reinforcement 15, running between bands 2, placed over the longitudinal fragment.

25 Fig. 6 is an enlarged cross-section of Fig. 1 at *f-f*, showing how several pairs of bands 2 may be added together to obtain greater strength. Pins 17 hold the pairs of bands 2 apart to allow the fireproof material to flow through openings 11.

30 Fig. 7 is an enlarged section of the stretching and locking device 19, showing the various details of 19, herein described, with 19 and the fragment of a pair of bands 2 embedded in the fireproof material 10.

Fig. 8 is a plan view of Fig. 7.

35 In the drawings, where similar numerals indicate similar parts, numerals 1 designate the forms for the concrete. Numerals 2 designate main wedgeshaped pairs of steel bands, or flat steel bars, which, together with their intervening concrete filling 16, form the main wedgeshaped supports which carry 40 the floors. Numerals 3 designate lateral wedgeshaped pairs of steel bands, which, together with their intervening concrete filling 16, form the lateral wedgeshaped supports which carry the floors. Numerals 4 45 designate flanges connected with bands 2 and with bands 3. Numerals 5 designate

holes in bands 2. Bolts 6 pass through holes 5. Main bands 2 support the lateral pairs of wedgeshaped bands 3. I place band reinforcements 15 between the pairs of main bands 2, or between the pairs of lateral bands 3, or between both. Numerals 10 designate the concrete. Flanges 4 are formed by a sharp bend along the one edge of band 2 and band 3, and form an acute angle i. e. 50 an angle which is less than 90°.

55 After having dealt with the above I am now coming to the final step in my invention, which enables me to cut down on weight, and increase the room height, in 55 fireproof buildings.

60 The reinforcement steel bands 2 carry the other reinforcements 3 and 15. These bands 2 stretch between the main steel frame 18, as shown in Fig. 1, and the final step, to 70 which I have referred, consists in rigidly anchoring said steel bands 2 to said frame 18, and to effectively do so I use an anchoring device which is adjustable, whereby I can properly stretch bands 2, when anchoring bands 2 to frame 18. By this stretching 75 method I immediately bring into effect the tensile resistance of the steel in bands 2, when the load is applied, without first having to take up any slack in bands 2, should 80 bands 2 not be properly tightened. In other words I add the application of the said tensile resistance, caused by said anchoring, to that resistance, against buckling, which is 85 obtained by the mere embedding of the reinforcements in the fireproof material.

90 In Fig. 1, which is a plan view of my invention, I have shown that the fireproof material 10, which may be concrete or any other suitable material, rests on the rectangular seats 9, and that the main reinforcement bands 2 carry said rectangular seats 9, and take up the tension caused by the weight of the floors. Numerals 18 designate the steel frame of the building. Numerals 25 designate 95 the steel columns which support frame 18. Numerals 1 designate the form upon which the fireproof material 10 is poured. Numerals 2 designate main pairs of wedge-shaped bands, which, together with the lateral pairs of wedgeshaped bands 3, form the 100 rectangular wedgeshaped seats 9. The floor

fireproof material 10 rests on seats 9. 15 designates reinforcements inside of the wedgeshaped seats 9. Numerals 16 indicate space, inside of the pairs of bands 2 and 3, 5 into which fireproof material 10 is inserted. 11 designate openings, between the spaced pairs of bands 2 and 3, through which the fireproof material 10 is filled into 16. Numerals 4 designate flanges, on bands 2 and on 10 bands 3, which hold the filling 16 in place. The ends of the band reinforcements 3 have sloping ends adapted to rest on the sloping sides of bands 2, and the ends of reinforcements 15 have sloping ends adapted to rest 15 on the sloping sides of seats 9. Numerals 19 designate an adjustable locking device, whereby I rigidly anchor bands 2 to steel frame 18. Said locking device consists of: Clamps 20 having clasp 21 and flange 22; 20 hook 23 which is attached to bands 2 by means of bolt 6 which passes through hole 5; and wedges 24. Bands 2 rest on the elongations 26 of 20.

Clasp 21 has a solid grip on the steel 25 frame 18 as shown in the drawings. Flange 22 and hook 23 overlap each other. Wedge 24 is inserted between flange 22 and hook 23. The base of wedge 24 rests against flange 22, and, when wedge 24 is driven, the sloping 30 sides of wedge 24 will tighten hook 23.

When the pairs of reinforcement bands 2, the pairs of reinforcement bands 3, which together form seats 9, the reinforcements 15, and the locking device 19 are in place, 35 wedges 24 are driven, whereupon bands 2 tighten and become rigidly anchored to the steel frame 18. By driving wedges 24 reinforcements 2 are initially tensioned and locked to frame 18 before the infilling 10 40 is poured.

The fireproof material 10 is thereupon poured, and 2, 3, 15 and 19 become embedded in the fireproof material 10. After the fireproof material has set, and after the forms 45 1 are removed, the fireproof floor stretches between, and rests on, the top of the flanges of frame 18. The adjustable locking device 19 is greatly strengthened by being embedded in the fireproof material 10.

By the stretching process of bands 2, which, as described, rigidly anchors the same to the steel frame 18, I obtain the grip, which immediately brings the tensile strength of the steel bands 2 into play, when 55 the weight on the floors is applied. That grip, which is created by said anchoring, is entirely independent of the grip, which the fireproof material has on bands 2 due to the cohesion between the fireproof material and 60 the steel, and which ceases to exist if the fireproof material slips on the steel. The added grip, caused by the stretching process of the anchoring of bands 2 to the steel frame 18, gives an additional margin of 65 safety, which makes it justifiable to cut

down on the steel and reduce the thickness of the floors, and thereby increase the height of the rooms.

It is evident that I can apply the herein described process, to stretch and lock the reinforcement bands, equally well in floors and beams of concrete buildings as in steel frame buildings.

Other modifications of construction may be made without departing from the spirit 75 of my invention.

I claim:

1. In the wedgeshaped band reinforcements of an infilled floor structure means connecting said band reinforcements with 80 the supports of said structure, said means adapted to stretch said bands, whereby said band reinforcements are put into tension and interlocked with said supports before the infilling takes place.

2. In the reinforcements of an infilled floor structure main pairs of wedgeshaped bands in combination with lateral pairs of wedgeshaped bands, said lateral bands having sloping ends adapted to rest on the sloping sides of said bands, and means whereby said main bands are stretched and interlocked with the supports of said structure before the infilling takes place.

3. In the reinforcements of an infilled floor structure main pairs of wedgeshaped bands in combination with lateral pairs of wedgeshaped bands, said lateral bands having sloping ends adapted to rest on the sloping sides of said main bands, members attached to said main bands and overlapping the supports of said structure, and wedges driven between the overlapping parts of said members and said supports, whereby said main bands are put into tension and interlocked with said supports before the infilling takes place.

4. In a fireproof building main pairs of spaced wedgeshaped bands in combination with lateral pairs of spaced wedgeshaped bands, said lateral bands extending between said main bands and having sloping ends adapted to rest on the sloping sides of said main bands, whereby rectangular wedgeshaped seats are formed to carry the fireproof material, means to hold said fireproof material in place inside of said pairs of bands, reinforcements intermediate the sloping sides of said rectangular seats, said pairs of main bands extending between the supporting frame of said building, and means whereby said main bands are stretched and rigidly anchored to said frame.

5. In a fireproof building main pairs of spaced wedgeshaped bands in combination with lateral pairs of spaced wedgeshaped bands, said lateral bands extending between said main bands and having sloping ends adapted to rest on the sloping sides of said main bands, whereby rectangular wedge-

shaped seats are formed to hold the fireproof material, means to hold fireproof filling in place inside of said pairs of bands, reinforcements having sloping ends adapted to rest on the sloping sides of said rectangular seats, said pairs of main bands extending between the supporting frame of said building,

flanges attached to said supporting frame, hooks connected with said main bands, said hooks and said flanges overlapping each other, and wedges intermediate said flanges and said hooks.

HENRY SORENSEN.
